UNITED STATES PATENT OFFICE.

JAMES V. WASHBURN, OF WATERBURY, CONNECTICUT.

PENHOLDER.

SPECIFICATION forming part of Letters Patent No. 683,715, dated October 1, 1901.

Application filed September 17, 1900. Serial No. 30,235. (No model.)

To all whom it may concern:

Be it known that I, JAMES V. WASHBURN, a citizen of the United States, residing at Waterbury, in the county of New Haven and 5 State of Connecticut, have invented an Improvement in Penholders, of which the following is a specification.

Heretofore and because of corrosion and thickened ink it has been difficult to remove 10 pens from penholders after a period of continued use. This condition arises largely because penholders are usually made with concentric surfaces between which the pens have been received, and this construction really 15 assists the corroding of the pen and the elongating up of the holder, and my invention is designed to overcome these difficulties.

In carrying out my invention the pen is received within the tubular end of the holder 20 and is held against the inner surface thereof by a suitable lever pivotally connected to a suitable support and arranged to swing longitudinally of the tubular end. In my improvement the pen is held between the said 25 inner surface of the tubular end and an edge of the said lever and is released by swinging the lever into its open position. Usually when the lever is in the open position the pen will fall out of the tubular end by gravity; 30 but if the pen adheres to the tubular end a slight blow will release the same without the necessity of applying force. The said support is to be connected to the penholder in any desired manner.

35 In the drawings, Figure 1 is a longitudinal section and partial elevation. Fig. 2 is a longitudinal section and partial elevation at right angles to Fig. 1, and Fig. 3 is an end view, representing a form of my invention. 40 Fig. 4 is a longitudinal section and partial elevation, and Fig. 5 a longitudinal section and partial elevation at right angles to Fig. 4, representing a form of my invention. Fig. 6 is a longitudinal section and partial elevation, and Fig. 7 an end view, showing a form 45 of my invention. Fig. 8 is a longitudinal section and partial elevation specially illustrating a form of support within the tubular end; and Fig. 9 is an end view of the tubular end 50 and lever, showing still another form of my invention.

The handle *a* may be of any desired mate-

rial and is preferably provided with a reduced end *b*, over which the tubular end *b*, preferably of metal, is received and held to the handle. *c* represents a lever arranged longitudinally of the tubular end *b* and adapted to engage the pen *e* between the curved inner surface of the tubular end and an edge of the said lever, the release of the pen being effected by swinging the lever into its open position. This lever *c* is pivoted to a suitable support *d*, provided therefor, and which support is connected to the penholder. This support is preferably within and extending across 65 and longitudinally of the tubular end. The lever is preferably made of sheet metal pivoted to the support.

In Figs. 1 and 4 the lever is shown in a gripping position in full lines and in the open 70 position in dotted lines, and in Figs. 3, 6, 7, and 9 in a gripping or closed position in full lines alone and the free or handle end *3* of the lever being adapted to be grasped to effect the swinging of the same in gripping and 75 releasing the pen. The support to which the said lever is pivotally connected I prefer to make in the form of a plate of metal or other suitable material which has one edge in part reduced to provide for the insertion of the 80 pen into the tubular end. Figs. 4 and 5 show a single plate or blade of metal extending across and longitudinally of the tubular end and received in a slot in the reduced end of the handle, the said lever being pivoted upon 85 one face of the said plate. The said plate may be provided, as shown in Fig. 4, with an open center, so as to lighten the plate and reduce the weight of metal without interfering with the stiffness of the plate. In Figs. 90 1, 2, and 3 the said lever is shown as pivoted between two plates or blades received in adjacent slots in one end of the handle. Both of said blades, however, may be placed in the same slot, although a better hold is obtained 95 by employing two slots. It will be noticed that in Fig. 1 the said lever *c* in its engaging position, as shown in full lines, has the handle end outside of and parallel with the tubular end *b* and that the dotted or open position 100 of the lever brings the handle end substantially within the parallel sides of the tubular end *b*. The advantage of this construction is that the projecting or handle end when

the penholder lies upon a desk serves to prevent the penholder rolling.

In the form of lever shown in Figs. 4 and 5 it will be noticed that when the same is in its gripping or closed position, as shown in full lines, the handle end comes substantially within the parallel sides of the tubular end and that when in the open position (shown in dotted lines) the handle end of the lever projects outside of the tubular end *b*; but I do not limit myself in any respect to the form of lever or support as shown or to the position which either of the same may occupy.

15 In Figs. 6 and 7 a band *f* surrounds the tubular end and the free ends of the band are parallel, and between them the lever *c* is pivoted by the pin 4, and the said tubular end is recessed or so formed as to receive the 20 said lever and permit the same to swing, so as to coact with the tube in holding the pen in place.

In Fig. 9 the tubular end is itself made with 25 projections or lugs *g* adjacent to the outer end and between and to which the lever *c* is pivotally connected, this latter form being the simplest form of the invention. Fig. 8 shows a form of internal support for the lever, in which said support, as a blade, is provided with a lug or projection *g*, passing into 30 a perforation in the tubular end *b* for the purpose of holding the support within the tubular end. More than one lug or projection *g* may be employed, if desired. All of 35 the said levers are so formed that in the open position the contacting edge is free from the pen, and when in the closed position the pen is pressed against the inner surface of the tubular end *b* by an edge of the said lever brought into position by the swinging action, 40 which edge is slightly eccentric or farther from the pivot than the portion brought into opposition in the open position.

I claim as my invention—

45 1. The combination with the handle and tubular end of a penholder, of a support in the form of a plate extending across within and longitudinally of the tubular end and a swinging pivoted lever arranged within and longitudinally of the tubular end and pivoted to 50 the said support, so that the pen is held between the inner surface of the tubular end and an edge of the said lever or is released by swinging the lever on its pivot, substantially as set forth.

55 2. The combination with the handle and tubular end of a penholder, of a support in the form of a plate extending across within and longitudinally of the tubular end, and a lever

consisting of plate of metal within and extending longitudinally of the tubular end and pivoted to the said support and adapted in one position to hold the pen between the inner surface of the tubular end and an edge of the said lever, and to release the pen when 60 65 swung into the reverse position, substantially as set forth.

3. A penholder-handle having a lengthwise slot at one end and a tubular end surrounding the same, a support in the form of a plate or 70 blade of metal extending lengthwise through across the tubular end and received and held within said slot, and a pivoted swinging lever arranged within and longitudinally of the 75 said tubular end and pivotally connected adjacent to the free end of the said blade of metal and adapted in one position to hold the pen between the inner surface of the tubular end and an edge of the said lever or to release the pen in a reverse position, substantially as 80 85 set forth.

4. The combination with the tubular metal end, of a handle having a reduced end longitudinally slotted and adapted to fit into the said tubular end, two substantially parallel 90 longitudinally-extending blades received in the slotted reduced end of the handle, and a swinging edgewise-gripping lever between and pivoted adjacent to the free ends of said blades and adapted in one position to hold 95 the pen between the inner surface of the tubular end and an edge of the gripping-lever or to release the same in the opposite position, substantially as set forth.

5. The combination with the tubular metal 95 end, of a handle having a reduced end longitudinally slotted and adapted to fit into the said tubular end, a blade of metal extending lengthwise through across the tubular end and received and held within said slot and having 100 a reduced portion, and a lever of sheet metal having an eccentrically-arranged portion pivoted adjacent to the free end of said blade and an extending free end to be grasped by the finger and arranged within and longitudinally of the tubular end and parallel with the said blade of metal so as to hold the pen between the inner surface of the tubular end and an edge of the said lever and to release 105 the pen when the lever is swung into the opposite position, substantially as set forth.

Signed by me this 13th day of September, A. D. 1900.

JAMES V. WASHBURNE.
